UNITED STATES PATENT OFFICE.

JOHN H. BELL, OF SOUTH ORANGE, NEW JERSEY, ASSIGNOR TO WESTERN ELECTRIC COMPANY, INCORPORATED, OF NEW YORK, N. Y., A CORPORATION OF NEW YORK.

TELEGRAPH SYSTEM.

Application filed December 4, 1918. Serial No. 265,241.

To all whom it may concern:

Be it known that I, JOHN H. BELL, a citizen of the United States, residing at South Orange, in the county of Essex, State of

5 New Jersey, have invented certain new and useful Improvements in Telegraph Systems, of which the following is a full, clear, concise, and exact description.

This invention relates to telegraph systems and more particularly to so-called capacity systems, wherein a line conductor may have high electrostatic capacity characteristics as usually encountered in submarine cable working.

10 15 The principal object of this invention is to provide an improved organization of apparatus for the transmission of telegraphic impulses in the form of so-called "block" signals.

20 In the telegraph art, it is commonly understood that in systems, wherein currents of one polarity are employed for the transmission of "dot" signals and currents of the opposite polarity are employed for the 25 transmission of "dash" signals, some gain in transmission may be had by providing that instead of sending a plurality of successive impulses of current, which may correspond with either a group of dot or a

30 group of dash signals, no interruption of the current will take place during the transmission of a group or series of signals formed by impulses of one and the same polarity. Such continuous application of potential in substitution of a plurality of signals usually requiring a plurality of successive impulses of like polarity is commonly referred to in the art as block signals.

35 Signals of this character also serve to prevent so-called wandering zero effects and when received through the operation of a suitable tape recorder may be read by noting the length of tape which may have passed through the receiver. In the case of automatic repeaters block signals may be trans- 40

45 lated due to a polarized line relay at a receiving station continuing on either so-called "spacing" or "marking" bias as well understood in the art.

50 In providing a system for more effectively and efficiently handling telegraphic transmission of this nature, the present invention provides an arrangement of relays interconnected in such a manner that they 55 may serve as pole changers under the con-

trol of respective pluralities of brushes, which are, in turn, controlled by means of a suitably notated or perforated transmitting tape.

This invention is illustrated in the accompanying drawing in which, for the sake of clearness, only so much of a telegraphic transmitting system has been shown as will be necessary to a clear understanding of the features of the system. 60

65 Referring to the drawing, Fig. 1 is a diagrammatic illustration of a transmitting system in accordance with this invention, while Fig. 2 shows in theoretical form such signalling current curves as may serve to 70 convey a clear understanding of the service results sought in the present system.

75 In describing the operation of this system, reference will be had to the drawing, in which the reference character L indicates a duplexed line or cable conductor, which may be understood as extending to a distant station (not shown). The outgoing lead of the cable stands normally connected through the contacts 4 of a compound-wound relay 1, and the contacts 14 of a second compound-wound relay 11 to an earth connection 7. This earth connection is for the purpose of 80 draining the cable of any currents which may remain therein due to the transmission of signals, as will presently appear. For the control of local circuits of the transmitting system, a local battery 20 is connected common to a shaft 21 which carries a suitable metallic drum 22. A series of guide or feed pins 23, carried by this drum, are arranged to mesh with a series of guide perforations 25 extending centrally through the length of a transmitting tape 24. Perforations 26-29, in this tape, are arranged to 85 pass under a pair of brushes 30 and 31 as the tape is moved from right to left in the direction of the arrow, by a suitable means not shown.

90 The brushes 30 and 31 are so spaced with respect to the brush 30 being in advance of brush 31 that the perforations 26-28 will permit both brushes to make contact with the drum 22 at proper instants; that is, the brush 30 may be just entering a perforation at the instant the brush 31 will be just leaving the same perforation. The spacing distance from center to center of the perforations 26-28 is such that at proper moments, corresponding with intervals between 95

100 105 110

successive impulses of like polarity, which in each case are represented by successive recurring perforations, both brushes may be making contact with the drum 22 at the 5 same time, i. e., at the instant the brush 31 may be entering a perforation, as the perforation 27, the brush 30 will be just leaving a perforation, as the perforation 26, and engaging the tape space intervening 10 between the two holes. In turn the brush 31 may be just entering the perforation 28 at the instant the brush 30 is leaving the perforation 27.

During the time the brushes may be in 15 the position shown in the drawing, current from battery 20 may flow through the brush 30 and the operating winding 13 of the relay 11. On this relay the winding 12 is so proportioned with respect to the 20 energizing battery 20 that while it may exert sufficient force to retain the armature of this relay in an operated position, it will not, however, develop sufficient strength to 25 operate or move the armature of this relay from its normal position. In the transmission example, assumed and represented by the perforations 26, 27, 28, 29 and 35 in the tape, it may be pointed out that at the time the perforation 26 passed under 30 the brush 31, current from the battery 20 through this brush and the winding 12 of the relay 11 would not have caused the operation of this relay, since the winding 12 is proportioned to develop only sufficient 35 strength to retain the armature of the relay in its operated position as described. When the first perforation 26 comes under the brush 30, however, a circuit will be completed from the battery 20 through the 40 winding 13 of the relay 11 and therein develop sufficient strength to operate this relay. At an instant just before the first perforation 26 passes from beneath the brush 30, thereby causing disconnection of current 45 through the winding 13, the brush 31 will have entered the perforation 27 to establish current through the winding 12 whereby the armature of the relay 11 will be held in its forward position. During the 50 time the relay 11 continues operated, a circuit may be traced from the earth connection 7 by way of the contacts 15 of the relay 11 to the positive pole of a line battery 6, continuing through this battery and the 55 normal contacts 4 of the relay 1 to the cable L.

As the tape advances, the brush 30 will enter the perforation 27 just before the brush 31 leaves this perforation, therefore, 60 current will continue through the holding winding 12 during the time the brush 31 may be insulated by the tape intervening between the perforations 26 and 27. In turn just before the perforation 27 leaves the 65 brush 31 the brush 30 will have also entered

this perforation and established current through the operating winding 13 to continue the energization of the relay 11 during the period the tape intervening between the holes 27 and 28 is passing underneath 70 the holding circuit controlling brush 31. As the perforation 28 passes beneath the brush 31 the holding winding 12 will receive current to lock the relay 11 while the brush 30 is traversing the tape between the perforations 75 27 and 28. In turn the brush 30 will enter the perforation 28 before the brush 31 leaves this opening and current through the winding 13 will retain the relay 11 operated until the perforation 28 passes 80 from beneath the brush 30, whereupon the relay 11 will be disconnected to permit its release.

From the foregoing description, it will be clear that during the time the successive 85 perforations 26, 27 and 28 may be passing beneath the brushes 30 and 31 instead of three separate negative impulses being imparted to the line conductor L, a negative voltage would have been effective with the 90 line conductor, having duration from the moment the brush 30 entered the perforation 26 until the moment the perforation 28 passed from beneath the same brush 30.

During the time the tape intervening between the perforations 28 and 29 is passing beneath the brushes 30 and 31, a single perforation 35, which may correspond with an impulse of positive current to the line may arrive at and pass beneath the brushes 36 100 and 37. Although in passing beneath the brush 37, the perforation 35 will permit current from the battery 20 to complete circuit through the winding 2 of the relay 1, this relay will not be operated due to the 105 fact that this marginal winding is so proportioned that while it may serve as a holding winding to retain the armature of this relay in its operated position, it will not develop sufficient strength to move the armature of this relay from its normal position, the margins being similar to those already described in connection with the winding 12 of the relay 11. When the perforation 35 arrives under the brush 36, however, current from the battery 20 through the winding 3 will cause the operation of the relay 1, and since, at such time, the brushes 30 and 31 are insulated on the tape intermediate the perforations 28 and 29, the relay 11 will stand disconnected and therefore be in its normal position. The operation of the relay 1, in response to current through the winding 3, as established by the brush 36, will complete a circuit which may be 115 traced from the earth connection 7 through the normal contacts 14 of the relay 11 to the negative pole of the line battery 6. After continuing through this battery, the circuit extends through the forward contacts 5 of 120 130

the relay 1 to the line conductor L, thereby imparting an impulse of positive current over the line. Since only a single impulse of negative current is desired in the assumed 5 combination of perforations in the tape 24, the relay 1 will only continue energized during the time the perforation 35 may be traveling underneath the brush 36, which controls the operating circuit of the relay 1. 10 As the tape advances, the brush 31, although entering the perforation 29, which corresponds with an impulse of negative current, will not cause the operation of the relay 11 due to the fact that this brush controls the 15 marginal or holding winding 12 of the relay 11. When the perforation 29 comes under the brush 30, however, current from the battery 20 through the winding 13 will cause the operation of the relay 11 to close its forward contacts 15 and since the brushes 36 and 37, which correspond with the control of positively poled impulses to the line L, will be continuing insulated by the tape, negative current will again be established 20 over the contacts 15 of the relay 11 and the normal contacts 4 of the relay 1 with the line conductor L.

In considering the electrical effects produced by transmission of the five impulses 30 just described with respect to the line L, reference will be had to Fig. 2 of the drawing in which the irregular shaded line at A may be considered as indicating a series of 35 impulse intervals corresponding with the perforations present in the tape 24. Assuming that these impulses may have been transmitted by the usual methods, a current line similar to that shown by the shaded line B would have resulted with respect to the 40 receiving end of the cable L. For convenience of description, the two dot and dash lines E, respectively, above and below the zero potential line O may be considered as representing the efficiency line of the positive and negative impulses, that is, at the receiving end of the cable, it will be necessary for the current to rise to a strength indicated by this line in order to properly 45 influence the receiving devices. As indicated in this shaded current line, the first positive impulse would result in a current slightly in excess of the efficiency line, while the second and third impulses of like polarity would merely form waves progressing 50 in an ascending scale with regard to electrically charging the line conductor. Therefore, on the fourth or negative impulse being applied to the cable, the previous positively poled current charge therein 55 would not be sufficiently overcome to permit this negative impulse to build up to the necessary efficiency strength E, although the fifth impulse being of positive polarity, may rise to a proper value as shown. The condensers 15 and 16 which comprise the ratio

arms of the duplex equipment serve in a measure as blocking means for preventing an excess building up of current strength in the cable, and serve to cause the impulses to have what may be termed more abrupt or 70 steep wave front.

Under the present system the five impulses illustrated at A would be handled by the transmitter in a manner as may be illustrated by the shaded line at C, while the 75 actual effects of these currents at the receiving end of the cable may be considered as corresponding with the curved line shown at D. These currents as received are in the form of a sharp rise in current corresponding 80 with the first current impulse and since this application of current continues without interruption through the duration of the three positive impulses, the condensers 15 and 16 continue charged and the resulting 85 effect with the cable is that the current would gradually fall therein to approximately the zero line as shown. It will therefore be clear that although the single fourth negative impulse follows three successive 90 positive impulse intervals, it will not be opposed but may build up to a slightly greater strength than required by the efficiency line E, and in turn the fifth or positive impulse 95 may also build up to a proper value as shown.

The duplex equipment also comprises receiving devices 17 connected from the line L to an artificial line indicated as AL and by comparing the current line A (Fig. 2) with 100 the current line C or the current line B with the current line D, it will be clear that an increased number of wave effects are present by the usual transmission method A and B, whereby a greater number of surge 105 or stray current impulses may be present to adversely affect the receiving devices 17. It is well understood in the art that under working conditions in exact balance of an artificial line with respect to a real line or 110 cable may frequently exist and under such condition changes of current set up by the transmitting devices may interfere with the home or local receiving devices, and accordingly, inspection of the current line C and D 115 (Fig. 2) which are characteristics of the present system, will clearly reveal a material reduction in the number of current changes therefore corresponding bettering of the condition for the proper working of the 120 home receiving devices as the device 17, may result through the present system.

From the foregoing description, it will be clear that by means of the present organization of apparatus a continuous application 125 of current may be substituted for successively recurring impulses of like polarity, and it will also be clear that such intervals of current with a line conductor may correspond in the matter of time duration exactly 130

with the beginning and ending of a series of impulse intervals as represented by the perforations in a transmitting tape, i. e., at the instant a controlling brush encounters a perforation, current will be applied to a cable and such current interval will continue until such instant as the same controlling brush may leave the last perforation in a series of perforations representing successive impulses 10 pulses of like polarity.

What is claimed is:

1. In a telegraph system, a line, a transmitting tape, a plurality of sets of contact brushes, the brushes of each set being positioned in tandem with respect to said tape and cooperating therewith to send signaling impulses to the line, the polarity of the line impulses being different for each set of brushes, and means dependent upon the 20 longitudinal distance between successive perforations in the tape for determining the duration of the transmitted impulses.

2. In a telegraph system, a line, an impulse transmitting device comprising a 25 drum of conducting material, a perforated transmitting tape, a plurality of sets of contact brushes, the brushes of each set being positioned in tandem with respect to said tape and arranged to make contact with said 30 drum through perforations in said tape for transmitting signaling impulses to the line, the polarity of the line impulses being different for each set of brushes, and means dependent upon the longitudinal distance 35 between successive perforations in the tape for determining the duration of the impulses transmitted to the line.

3. In a telegraph transmitting system, a line conductor, a notated transmitting tape, 40 a plurality of brushes positioned tandem with respect to said tape, and electroresponsive means controlled by said brushes to continuously apply potential to said line during a period predetermined successive 45 notations on said tape may be effective with the brushes.

4. In a telegraph transmitting system, a line conductor, tape means, a pair of brushes positioned tandem with respect to said tape, a compound wound relay controlled by said brushes, and means controlled by said relay for continuously applying potential to said line during intervals otherwise corresponding with periods during which successive impulses of like polarity would be required. 50

5. In a telegraph transmitter, a transmitting tape, a line conductor, a first pair of brushes set tandem with respect to said tape, a compound wound relay controlled by said 60 brushes, a second pair of similarly arranged brushes and a relay controlled thereby, and means controlled by each pair of said brushes to render the associated relay effective to apply a single interval of potential 65 to said line in substitution of successive intervals of current of like polarity.

6. In a telegraph transmitting system, a notated tape, a line conductor, a plurality of brushes to track said tape, a compound 70 wound relay having windings respectively energized by said brushes, and means controlled by said relay for applying a single interval of potential to said line in substitution of a plurality of impulse intervals of 75 like polarity.

7. In a telegraph transmitting system, a line conductor, a notated tape, a plurality of pairs of brushes for tracking said tape, a plurality of relays, a plurality of windings 80 for said relays respectively controlled by the brushes of said pairs, means controlled by said relays for normally grounding said line conductor, and means controlled by said pairs of brushes respectively to continuously energize a respective one of said relays in applying potential to said line conductor. 85

In witness whereof, I hereunto subscribe my name this 22nd day of November, A. D. 90 1918.

JOHN H. BELL.
